US00D799835S

(12) **United States Design Patent** (10) **Patent No.:** **US D799,835 S**
Okai (45) **Date of Patent:** **** Oct. 17, 2017**

(54) **ORAL CARE IMPLEMENT**

(71) Applicants: **COLGATE-PALMOLIVE COMPANY**, New York, NY (US); **OMRON HEALTHCARE CO., LTD.**, Kyoto (JP)

(72) Inventor: **Takahide Okai**, Highland Park, NJ (US)

(73) Assignee: **COLGATE-PALMOLIVE COMPANY**, New York, NY (US)

(**) Term: **15 Years**

(21) Appl. No.: **29/547,157**

(22) Filed: **Dec. 1, 2015**

(51) LOC (10) Cl. **04-02**

(52) U.S. Cl.

USPC **D4/101**

(57) **CLAIM**

The ornamental design for an oral care implement, as shown and described.

DESCRIPTION

FIG. 1 is a front right perspective view of an oral care implement according to the new design;

FIG. 2 is a rear left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines represents parts of the article that form no part of the claimed design.

1 Claim, 4 Drawing Sheets
